UNITED STATES PATENT OFFICE.

WILLIAM KOSICKY, OF DETROIT, MICHIGAN.

BAKER'S OVEN.

SPECIFICATION forming part of Letters Patent No. 727,544, dated May 5, 1903.

Application filed July 9, 1902. Serial No. 114,859. (No model.)

To all whom it may concern:

Be it known that I, WILLIAM KOSICKY, a citizen of the United States, residing at Detroit, in the county of Wayne and State of Michigan, have invented certain new and useful Improvements in Bakers' Ovens; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to bakers' ovens; and it consists in the construction and arrangement of parts hereinafter fully set forth, and pointed out particularly in the claims.

20 The object of the invention is to provide an oven of the character described in which the arrangement is such as to provide for a continuous and uniform baking, to provide for regulating the temperature of the oven in a manner to maintain it at the requisite degree of heat, and to provide for cooling the oven without interfering with the fire or cooling the flues which convey the products of combustion to the stack. A further arrangement provides for the introduction of steam into the oven at a point to effect a uniform diffusion thereof.

25

The above object is attained by the structure illustrated in the accompanying drawings, in which—

30 Figure 1 is a central longitudinal section through the oven as on line 1 1 of Fig. 3. Fig. 2 is a front elevation of the oven. Fig. 3 is a vertical transverse section at the front end of the oven on line 3 3 of Fig. 7. Fig. 4 is a horizontal section on line 4 4 of Fig. 1. Fig. 5 is a horizontal section on line 5 5 of Fig. 1. Fig. 6 is a horizontal section on line 6 6 of Fig. 1. Fig. 7 is a horizontal section on line 7 7 of Fig. 1.

35 Referring to the characters of reference, 1 designates the main walls of the oven, which, together with the other structural parts, are made, preferably, of brick. At the bottom of the structure is the usual ash-pit 2, flanked on either side by hollow spaces which extend

longitudinally of the structure and are filled with sand 3 for the retention of heat.

The fire-space 4 is of suitable structure and provided with a grate 5. Leading from the fire-space is the combustion-chamber 6, through which the products of combustion pass rearwardly on either side of the dividing-partition 7 through the flues 8, which lead into the lower side flues 9, (see Fig. 4,) that extend forwardly to the front end of the structure and communicate with the lower ends of the vertical flues 10, whose upper ends discharge into the upper horizontal flues 11, which pass horizontally of the structure and at their rear ends communicate with the upper side flues 12, which lead forward to the stack, (not shown,) located at any suitable point. It will therefore be seen that the product of combustion after leaving the combustion-chamber 6 is divided and passes through the lower central flues 8 into the side flues 9, thence forward to the vertical flues 10, from which it is discharged into the upper flues 11, in which said current passes rearwardly of the structure and is discharged into the upper side flues 12, communicating with the stack, whereby said current is made to travel back and forth through the structure below and above the oven proper, 13, which occupies a central position in the brick-work and is subject to the action of the heat upon all sides thereof.

35 Formed in the structure below the oven is an air-chamber 14, which is immediately above the fire-space and the return-flues 9, whereby the air contained in said chamber becomes intensely heated, which heat is imparted to the hearth of the oven. Located in the front wall 15 are the draft-doors 16, which communicate with the forward end of the chamber 14, and leading from the rear end of said chamber are the vertical flues 17, which pass upwardly through the rear wall and are controlled by sliding dampers 18, operated through the medium of the rods 19, passing longitudinally of the structure, as shown by dotted lines in Fig. 7. By opening the doors 16 and the dampers 17 cold air may be caused to pass through the chamber 14, thereby reducing the temperature of said chamber and cooling the hearth-oven 13, as may be re-

quired, without admitting cold air directly into the oven. This cooling of the chamber 14 is accomplished without in any manner interfering with the combustion-chamber or the flues leading therefrom, which communicate with the stack, obviating the waste of fuel incident to the cooling of the combustion-chamber and its communicating passages and maintaining the heat within the structure, so that the temperature of the oven may be readily increased by closing the draft-openings communicating with the chamber 14.

The front of the oven 13 is closed by a suitable door 20, and connected with the rear of the oven is a central vertical flue 21, adapted to be controlled by the slide-damper 22. Should it be desirable to admit cold air directly into the oven, the door 20 is opened, as well as the damper 22, when a current of cold air is allowed to pass directly through the oven. As the flue 21 has no communication with the smoke-flues of the structure, the cooling of the oven in the manner above described does not cool down the fire nor cool the smoke-flues communicating with the fire-space, so that the cooling of the oven is purely local and does not result in a waste of heat or fuel. The upper side flues 12 are caused to communicate with the stack (not shown) through the openings 24 (shown by dotted lines in Fig. 3) and controlled by the slide-dampers 25, operated through the rods 26. These dampers are of course opened when the fire is started; but after the fire has burned down sufficiently they are closed to prevent the heat from passing into the stack.

The fire-space on either side of the grate is provided with a removable lining 26, of fire-brick, which protects the sides of the fire-space and allows of an easy replenishing of the lining when burned out.

Within the side wall of the fire-space is a water-coil 27, connected with a steam and water drum 28 by means of the pipe 29. Leading from the steam-space of the drum 28 is a pipe 30, which extends into the oven 13 and is joined to a cross-piece 31, having perforations in the upper arc thereof whereby steam is admitted into the rear of the oven or baking-chamber for the purpose of maintaining the requisite moisture therein during the operation of baking.

In the front wall of the structure is a ventilating-flue 32, closed by a suitable door 33. When the oven-door is opened, the heat and steam escaping from the oven may be directed into the ventilating-flue to prevent it from passing out of the oven into the bake-shop.

The gas-pipe 34 enters the opening 35 in the front of the oven and carries a gas-jet (not shown) for the purpose of illuminating the interior of the oven to enable the baker to determine the condition of the bread during the process of baking.

In the front wall of the structure are the lower doors 36, affording openings through which the lower flues 9 may be cleaned, and in the upper portion of the front are the doors 37, which afford access to the upper flues 12 for the purpose of cleaning.

Having thus fully set forth my invention, what I claim as new, and desire to secure by Letters Patent, is—

1. In an oven, the combination of the furnace, the lower horizontal flues and the upper horizontal flues connected at the forward end of the oven by vertical flues, a baking-chamber interposed between the upper and lower horizontal flues, an air-chamber interposed between the hearth of the oven and the lower horizontal flues, a vertical flue communicating with the rear of said chamber, a damper in said vertical flue and a draft-door in the front of said air-chamber for directing a current of air therethrough. 85

2. In an oven, the combination of the furnace, the baking-chamber, the fire-flues leading from said furnace and passing around said baking-chamber, an air-chamber below the hearth of the baking-chamber, draft-doors communicating with the front end of said air-chamber, vertical flues opening into the exterior air and communicating directly with the rear end of said air-chamber independently of the fire-flues whereby a cold current of air 95 may be passed through the air-chamber to cool the hearth of the baking-chamber without cooling the fire-flues.

In testimony whereof I sign this specification in the presence of two witnesses.

WILLIAM KOSICKY.
